A. BIRÓ ET AL

WINDOW REGULATOR BEARING

Filed Aug. 27, 1923

Patented Aug. 5, 1924.

1,503,470

UNITED STATES PATENT OFFICE.

ALBERT BIRÓ AND ERNEST E. HEINTZ, OF DETROIT, MICHIGAN.

WINDOW-REGULATOR BEARING.

Application filed August 27, 1923. Serial No. 659,491.

To all whom it may concern:

Be it known that ALBERT BIRÓ and ERNEST E. HEINTZ, citizens of the United States, residing at Detroit, in the county of Wayne and State of Michigan, have invented certain new and useful Improvements in Window-Regulator Bearings, of which the following is a specification.

This invention relates to bearings for window regulators, and has for its object a special form of window regulator bearing for mounting the upper drum or sprocket on the window regulator plate. This bearing also acts as an adjustable anchor for one end of the counter-balancing spring.

Another feature of the invention is the pressing in of the upper plate of the regulator to sink the lock nut at the end of the bearing stud below the level of the trimming that goes over the lock board.

In the drawings:

Fig. 1 is an elevation of the top part of a window regulator equipped with our improved bearing.

Fig. 2 is a section taken on the line 2—2 of Fig. 1.

Fig. 3 is a section taken on the line 3—3 of Fig. 2.

a designates the plate of the regulator which is ordinarily screwed to the lock board of the door (when the regulator is mounted in the door); *b* is the spacer bar, *c* the clutch housing containing a coiled spring clutch *d*, which need not here be described as it is described in the co-pending application of Ernest E. Heintz, Serial No. 583,721, and is of no importance in this application. A flexible cable *e* winds helically over the driving spool *f* and over the drum *g*. This drum *g* will be more generally referred to as a rotatable member, for so far as the invention of the bearing is concerned the drum might be a sprocket and the flexible cable a chain. This rotatable member will be preferably in the form of a stamping with a helical groove *h* rolled in its periphery. On the inside of the drum a boss or journal *j* is provided, which has a hollow interior for a purpose presently to be described. A screw machine product or stud *k* is provided with two diameters, one a reduced diameter that is externally screw-threaded as at *m*, and the other an enlarged diameter which forms a journal bearing *n* for the journal *j* formed by the internally projecting boss of the rotatable member.

The rotatable member is a cup-shaped or closed end cylinder member. This gives a hollow interior to house the spiral counter-balancing spring *o*, one end of which anchors in the journal bearing portion of the stud, while the other end of the same is anchored to a struck-out lug in the face of the rotatable member.

The lock or jam nut *p* screws onto the external threads *m* of the reduced portion of the stud, and when turned down firmly secures the stud to the regulator plate *a*. When this nut is loosened the stud may be turned with a screw driver inserted in the screw driver slot *q*, for the purpose of adjusting the stress of the spring. Be it noted that the regulator plate is pressed in as at *r*—or this might be termed cupped. This serves to countersink the end of the stud and lock nut below the level of the trimming *t* so that an undesirable bulge will not occur in the trimming.

The rotatable member or drum is easily mounted, as the boss simply fits into the journal bearing and the cap screw *s* can be screwed into the tapped interior of the stud, the head sinking into the recess of the boss or journal which is part of the rotatable member. This cap screw is provided with a spacing shoulder *n* which prevents the cap screw being screwed down so tight as to bind the rotatable member so as not to rotate. This forms a very desirable construction for regulators. The cap screw, nut, and the stud can all be made on an automatic screw machine. The drum can be made as a stamping with a rolled-in helical groove on the periphery of the drum, or same can be satisfactorily die cast.

A desirable feature of this regulator bearing is that the drum can be secured to the journal bearing before the spring is put under torsional strain. The torsional strain may then be imparted to the spring and the lock nut turned down to maintain the parts in this position of torsional strain.

We are aware that it is not broadly new to adjust a counter-balancing spring of the window regulator by means of turning the anchor of the inner end of the spring after releasing a lock nut. However, the prior construction to which we refer uses a two-part sprocket wheel, and a pin and slot adjustment between the stationary wheel section on the regulator frame. We secure all these results simply by the use of our

special stud. Our stud also has an additional function of acting as the journal bearing for the drum, a feature not found in the construction to which we allude.

5. What we claim is:

1. In a window regulator bearing, the combination of a plate, a stud secured thereto provided with a hollow open end forming a journal bearing, a rotatable member having a cup-like journal adapted to fit into the hollow of the stud, and means passing through the center of the journal and anchored in the journal bearing for tying the two together for permitting them to rotate, one in the other.
2. In a window regulator bearing, the combination of a plate, a stud secured to the plate having a projecting hollow open end and also provided with a central tapped hole, a rotatable member provided with a projecting journal having an opening passing therethrough, said journal fitting into the hollow of the stud which forms the journal bearing and a screw threaded into the tapped hole of the stud for tying the journal and journal bearing together for permitting the journal to rotate in the journal bearing.
3. In a window regulator bearing, the combination of a plate, a stud secured in the plate and having a projecting end which is open and hollow to form a journal bearing, a rotatable member provided with a projecting journal which is provided with a hollow recess and also with a hole therethrough, the said stud provided with a central tapped opening, the said journal fitting into the journal bearing, and a cap screw passed through the hole of the journal and screwing onto the threads of the tapped opening of the stud, the head of the cap screw sunk in the recess of the journal.
4. In a window regulator bearing, the combination of a plate, a stud secured to the plate and provided with a projecting hollow end forming a journal bearing, a rotatable member provided with an inwardly projecting boss forming a journal to fit into the journal bearing, the said journal provided with a hollow interior and also with a hole of smaller diameter forming an intervening shoulder between the walls of the hole and walls of said interior, said stud being provided with a tapped hole, and a screw provided with a spacing collar, said screw passed through the hole in the journal and screwed into the threads in the

tapped hole in the stud, said spacing collar arranged to abut against the end of the stud so as not to bind the shoulder of the journal.

5. In a window regulator bearing, the combination of a plate provided with a pressed-in or cup-shaped portion, a rotatable member and a bearing therefor secured to the plate at the cup-shaped portion with portions of said bearing protruding through the plate and sunk below the general level of the plate by reason of being located in the depressed or cupped portion of the plate.

6. In a window regulator bearing, the combination of a plate provided with a depressed or cupped portion, a stud acting as a bearing secured on such depressed portion and having the rear of the stud protruding through the plate into the space formed by the cup, a nut screwing onto the rear end of the stud and located within the space formed by the cup, and a rotatable member supported to rotate on said stud but on the bossed side of the plate.

7. In a window regulator bearing, the combination of a plate, a stud, a jam nut for securing the stud to the plate, a cupped rotatable member rotatably supported by the stud, a counter-balancing spring supported by the rotatable member and anchored at its outside end to the rotatable member and at its inside end to the stud, whereby the torsional stress of the spring may be regulated by releasing the nut and turning the stud.

8. In a window regulator bearing, the combination of a plate, a stud having a threaded portion passing through the plate and having a projecting hollow portion forming a journal bearing, a cupped rotatable member having a projecting journal arranged to fit into the journal bearing, means for tying the journal and journal bearing together so that the journal will rotate in the bearing, a jam nut screwing onto the threads of the stud, for adjustably securing the same to the plate, and a spiral counter-balancing spring having one end anchored to the rotatable member and the other end anchored to the stud, said counter-balancing member contained within the hollow interior of the cupped rotatable member.

In testimony whereof they have affixed their signatures.

ALBERT BIRÓ.
ERNEST E. HEINTZ.
